TRANSPORTABLE INVALID LIFTER

Edwin L. Fischer, 22035 W. Carbon Mesa Road,
Malibu, Calif.

Filed May 22, 1963, Ser. No. 75,012

Term of patent 14 years

(Cl. D41—1)

FIG. 1 is a perspective view of a transportable invalid lifter showing my new design;

FIG. 2 is an end view thereof; and

FIG. 3 is a top view.

The dominant features of my design reside in the portions shown in full lines on the drawing.

The chair shown in dotted lines in FIG. 1 has been omitted from FIGS. 2 and 3 for convenience of illustration only.

I claim:

The ornamental design for a transportable invalid lifter, as shown and described.
